UNITED STATES PATENT OFFICE.

FRANK C. HOBBS, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

POCKET-BILLIARD-TABLE GULLY.

1,174,151.

Specification of Letters Patent.

Patented Mar. 7, 1916.

Application filed May 13, 1915. Serial No. 27,833.

To all whom it may concern:

Be it known that I, FRANK C. HOBBS, a citizen of the United States, residing at Muskegon, in the county of Muskegon and 5 State of Michigan, have invented new and useful Improvements in Pocket-Billiard-Table Gullies, of which the following is a specification.

This invention relates to gullies for 10 pocket billiard tables and its object is to provide a gully of strong and substantial metal construction which can be easily applied to a table to convey the balls from the various pockets to a gully box at one end 15 of the table.

Another and important object of my invention is, therefore, to provide a sanitary gully of metal construction which will not permit the accumulation of dirt or other 20 foreign matter therein and access to which can be readily had at all times for the purpose of removing dust by brushing or wiping with a cloth.

A further object of the invention is to 25 provide a gully through which the balls will roll without producing noise and also one which can be made in standard sections to be applied to tables of different sizes without the exercise of any particular skill. 30 The invention has other objects in view which will be pointed out hereafter in the detail description in connection with the accompanying drawings, in which—

Figure 1 is a top plan view of my im- 35 proved gully showing the outline of the table frame in broken lines; Fig. 2 is a longitudinal sectional view on the line 2—2 of Fig. 1, showing the gully embodied in a table frame; Fig. 3 is a transverse sec- 40 tional view on the line 3—3 of Fig. 2; Fig. 4 is a detail sectional view of one end of a gully showing the adjustable fastening means; Figs. 5 and 6 are, respectively, ele- 45 vation and plan views of the gully T; Fig. 7 is a detail sectional view showing the means for fastening the bars and channels together; Fig. 8 is also a detail sectional view.

Referring to the drawings, the gully com- 50 prises as a whole the main member 8 which extends longitudinally of the table from one end to the other thereof, a transverse end member 9, a transverse central member 10, a transverse member 11 at the other end 55 of the table and a short member 12 to receive balls from the end member 11 and

convey them to the main member 8. The transverse members are each located in the frame in proper position to receive balls from the end pockets of the table and the 60 central transverse member is located to receive balls from the middle pockets of the table. The main member of the gully is downwardly inclined from the end member 9 to the gully box which is indicated 65 generally by 14. The short member 12 inclines downwardly from the end member 11 to the main member 8.

My present invention is particularly adapted for use in connection with the gully 70 box covered by my application Serial No. 27,834 filed May 13, 1915 (which is indicated by 14 on the accompanying drawings) and in connection with the pockets covered by my companion application Se- 75 rial No. 27,835 filed May 13, 1915; but it will be understood that this invention is not limited to such use and may be embodied with other boxes and pockets with equally satisfactory results.

The gully members each comprise a pair of track bars 15 on which the balls roll, a pair of guide bars 16 and a pair of tubular top rails 17. All of these parts are made of metal stamped or pressed into proper 85 shape and the bars are preferably fluted or corrugated longitudinally to provide a curved side which is directed inwardly within the gully and with which the balls are adapted to engage. These curved sur- 90 faces are preferably provided with a covering 18 of rubber or other suitable material and the edges of the bars are crimped to engage and hold the edges of the covering, as shown more clearly in Fig. 7.

The gully members are preferably made in standard sections to facilitate the assembly thereof in tables of different sizes and also to simplify the manufacture and lessen the cost thereof. These sections are indicated by channel bands 19, one of which is secured at each end of each section by any suitable means, and for this purpose lugs 20 may be stamped from the bands to engage the edges of the bars, as shown in Fig. 105 7. The ends of the bands are preferably formed into tongues 19' which are bent over and around the top rails 17 and engaged with the channels (Fig. 8). These tongues are securely locked in the channels and for 110 this purpose the tongues may be recessed at the side edges at 17' and the flanges of

the channels pressed into said recesses and crimped over the tongues, as shown in Fig. 8. I may also provide tubular connectors 22 in the ends of the tubular top rails to overlap the joints thereof, as shown in Fig. 4, to facilitate the assembly of the parts and strengthen the construction.

The end members and central member are secured in the frame of the table by means 10 of rods 23 located in the ends of the top rails and provided at their outer ends with claws 24. The claws are adapted to engage the sides of the table frame and hold the end members in proper position, as shown 15 in Fig. 3, and for this purpose the rods are adjustable in the tubular rails and can be secured in adjusted position by the binding screws 25 operating in the movable split collars 26. It will readily be seen that the 20 end members can be easily adjusted and secured in their proper position in the frame and that the engagement of the claws with the side of the frame will hold them permanently in place. The main member 8 25 may be suspended from the table by hangers 28 or by any other suitable means.

Each of the transverse members is provided with a T-section, (Figs. 5 and 6), one 30 end of the main member 8 being engaged with the T 27 in the end member 9, one end of the short member 12 being engaged with the T 27' in the end member 11, and the T 27" in the central member 10 being arranged to discharge the balls from said central member into the main member 8. These T's may 35 be provided with rods 21 secured in the channel bands 19 to engage the tubular rails of the adjacent gully members. These T's are all made alike, as shown in Figs. 5 and 6, 40 of the same material and in the same manner as the other sections, the bars being properly formed to guide the balls while traveling from the transverse members to the main member.

45 My improved gully is of strong and substantial metal construction which can be easily made and assembled at low cost because of its simplicity and sectional construction. As hereinbefore mentioned, the 50 T-sections are all made alike and can be used interchangeably and the other sections of the members are also made alike and can be used interchangeably. All of these sections are made out of sheet metal which can be 55 easily worked and they are adapted to be assembled and fixed in position in a table frame without especial skill.

The open skeleton construction of the 60 gully prevents the accumulation of dirt and other foreign matter therein and insures that the gully is always clear for conveying the balls from the pockets to the box. If chalk, paper, cigar or cigarette ashes or stubs enter the gully they will immediately drop through to the floor and thus all dan-

ger of choking the gully is eliminated. The skeleton construction also has the effect of maintaining the gully in a sanitary condition because it presents no opportunity for the accumulation of dirt or other foreign matter and all of its parts are readily accessible for the removal of dust by brushing or wiping with a cloth.

In practice the balls pass from the pockets into the end members of the gully, at or adjacent to the ends thereof, and roll toward the T's at the center of said members which direct the balls into the main member, through which they roll into the gully box at the lower end of said main member. The short member 12 is provided to convey the balls from the end member 11 to the main member 8 to avoid dropping the balls from said end member into the main member which, at this end of the table, is located some distance below the end member. The balls roll on the bottom track bars 15, 15 and are guided by the bars 16, 16 against any tendency to jump out of the gully. This construction insures smooth and even rolling 90 of the balls and thereby avoids any possibility of crowding or jamming. The balls roll without producing any appreciable noise and the joints between the sections made by the abutting ends of the bars and their covering are such that no interruption of the travel of the balls is produced thereby.

I am aware that changes in the form and proportion of parts and details of construction of my improved gully may be made 100 without departing from the spirit or sacrificing the advantages of the invention and I therefore reserve the right to make all such changes as fairly fall within the spirit and scope of the invention.

I claim:

1. A pocket billiard table gully of skeleton form and comprising a plurality of longitudinally disposed bars spaced apart, said bars being concavo-convex in cross section and the convex sides thereof being inwardly directed within the gully.

2. A pocket billiard table gully of skeleton form and comprising a plurality of longitudinally disposed concavo-convex bars spaced apart to form tracks and guides for the balls, each of said bars being stamped from sheet metal and having a rounded side directed inwardly within the gully.

3. A pocket billiard table gully of skeleton form and comprising a plurality of longitudinally disposed concavo-convex bars spaced apart to form tracks and guides for the balls, each of said bars being stamped from sheet metal and having a rounded side directed 120 inwardly within the gully, and a covering 125 of soft material on said bars to be engaged by the balls.

4. A pocket billiard table gully of skeleton form and comprising a plurality of longitu- 130

dinally disposed bars spaced apart to form tracks and guides for the balls, each of said bars being stamped from sheet metal and having a rounded side directed inwardly 5 within the gully and crimped edges, and a soft covering on said rounded side having its edges engaged under said crimped edges.

5. A pocket billiard table gully of skeleton form comprising a pair of track bars 10 ranged in adjacent and parallel relation on which the balls travel, a pair of parallel guide bars arranged above and spaced apart farther than the track bars to retain the balls in proper position within the gully and upon 15 the track bars, and a pair of side rails connected with and supporting said track and guide bars.

6. A pocket billiard table gully of skeleton form and comprising a plurality of longitudinally disposed track bars and guide bars 20 spaced apart, side rails above said bars, and bands engaged with said side rails and passing under said bars.

7. A pocket billiard table gully consisting 25 of a plurality of skeleton sections, each of said sections comprising tubular side rails, and connectors arranged in the abutting ends of said rails to secure the sections together.

8. A pocket billiard table gully consisting 30 of a plurality of sections, each of said sections comprising a plurality of longitudinally disposed bars spaced apart, bands at the ends of said sections, and means on the bands engaging said bars.

35 9. A pocket billiard table gully of skeleton form and comprising a plurality of longitudinally disposed track bars spaced apart at the bottom of the gully, guide bars on opposite sides of the track bars and spaced 40 apart therefrom, a side rail above each guide bar, and means connected with the side rails for supporting the bars.

10. A pocket billiard table gully consisting 45 of a plurality of sections, each of said sections comprising a plurality of longitudinally disposed bars spaced apart and a pair of side supporting rails above the bars, and channel bands engaged with the bars at the ends of the sections, the ends of said bands 50 being engaged with said rails.

11. A pocket billiard table gully consisting 55 of a plurality of sections, each of said sections comprising a plurality of longitudinally disposed bars spaced apart and a pair of side supporting rails above the bars, and channel bands engaged with the bars at the ends of the sections, there being tongues on the ends of said bands bent around the rails and engaged with the chan- 60 nels.

12. A pocket billiard table gully of skeleton form and sectional construction and comprising a plurality of bars and tubular

side rails, bands at the ends of the sections engaging said bars and rails, and means 65 within the rails at the joints between the sections to secure the sections together.

13. A pocket billiard table gully comprising a transverse member at each end of the table arranged to receive balls from the respective end pockets, a transverse member at the center of the table to receive balls from the side pockets, said members being arranged in substantially the same horizontal plane, a longitudinally inclined member connected at one end with the transverse member 70 at one end of the table and extending beneath the center transverse member and to discharge position beneath the other end transverse member, a short member connect- 75 ed with said other end transverse member and extending above and discharging into the longitudinally inclined member, and a T in the center transverse member arranged to discharge balls into said longitudinally 80 inclined member.

14. A pocket billiard table gully of skeleton form comprising an inclined member extending longitudinally of the table from end to end thereof, a transverse member at 90 one end of the table connected with said longitudinal member and arranged to receive balls from the pockets at that end of the table and convey them to the longitudinal member, and transverse members located 95 above the longitudinal member at the other end and at the center of the table to receive balls from the adjacent pockets of the table, and discharging means connected with said last-mentioned transverse members to convey balls therefrom to the longitudinal member, all of said parts being made of standard 100 sections.

15. A pocket billiard table gully comprising a transverse member, and claws at the 105 ends of said member to engage the table.

16. A pocket billiard table gully comprising a transverse member, and claws adjustably mounted in the ends of said member to engage the table. 110

17. A pocket billiard table gully comprising a transverse member having tubular side rails, rods mounted in the ends of said rails, and claws on the outer ends of said rods to engage the table. 115

18. A pocket billiard table gully comprising a transverse member having tubular side rails, rods longitudinally adjustable in the ends of said rails, binding screws operating in the rails to secure the rods in position, 120 and claws on the outer ends of said rods to engage the table.

FRANK C. HOBBS.
